UNITED STATES PATENT OFFICE.

WILLIAM H. GALLUP AND LEE CHURCHILL, OF TROY, NEW YORK, ASSIGNORS
TO THE GALLUP NOVELTY WORKS, OF SAME PLACE.

SHIRT-WAIST.

SPECIFICATION forming part of Letters Patent No. 289,640, dated December 4, 1883.

Application filed June 28, 1883. (No model.)

To all whom it may concern:

Be it known that we, WILLIAM H. GALLUP and LEE CHURCHILL, of the city of Troy, county of Rensselaer, and State of New York, 5 have jointly invented a new and useful Improvement in Shirt-Waists, of which the following is a specification.

Our invention relates to certain improvements in the manner of making shirt-waists—10 a kind of garment used for children's wear, which are by them worn exteriorly, and made to hold up the skirt or pantaloons by their attachment at the waist thereof.

Shirt-waists have usually been made so that 15 the weight of the attached skirts or pantaloons was sustained on the shoulders of the wearer, which had the tendency to straighten out the shirts, so as to draw them down close to the body, and thus give a gaunt appearance to 20 the wearer from the removal of the gathered and laundered fullness of the garment. The capacity which small boys have for weighting down their pockets added to this tendency and the vertical strain upon the shirt-waist 25 producing it.

The object of our invention is to so make this class of garments that the vertical tension and strain upon them and the shoulders shall be removed therefrom and transferred to the hips 30 of the wearer, and this we accomplish by a method of making such garments, which is illustrated in the accompanying two plates of drawings, forming a part of this specification, in which there are three figures shown with 35 the same designation of parts by letter-reference used in all of them.

Figure 1 shows a shirt-waist made with our improvement, and the garment shown as open at the bottom of the front opening, with the 40 lower corners thrown back. Fig. 2 illustrates a view of the same shirt-waist that is shown at Fig. 1 with the front of the garment closed. Fig. 3 illustrates a longitudinal section of the parts, taken on the line $x' x'$ of Fig. 2.

45 The several parts of the garment thus shown are designated by letter-reference and their function explained as follows:

The letter A indicates the shirt-waist body,

O the neck-opening, and C the collar, the garment being shown as made to open vertically 50 at the front from the collar to the waist on the line of the fly F², and to be secured thereat by means of buttons T and button-holes, in the usual manner.

The letter D indicates a belt attached 55 exteriorly to the garment at the back thereof, as designated at $a a'$, and S S indicate straps on the shirt-waist exterior, under which straps the belt D is passed. On the straps are placed either buttons B or button-holes for the attachment of the skirt or pantaloons adapted at their waistbands for such connection. At the front the belt D passes beneath the underlap F¹ and overlap-fly F² by means of vertical slits I I at each side, made in the garment, 60 and the belt for a girth-connection and tension upon the hips of the wearer connects at its ends by means of a buckle, M, or other suitable means beneath the garment. Instead of a buckle, any well-known means for connecting 70 the ends of the belt may be used.

As the means for attaching the skirt or pantaloons to the shirt-waist would be the same whether the buttons were arranged on the latter and the button-holes made in the attaching garments or the position of the buttons and button-holes were reversed, our invention includes either of these transpositions of the buttons and button-holes.

As the purpose of the straps S is to make a 80 passage-way connection between the shirt-waist body and the belt, if desired, instead of the straps S, externally attached to the garment, parallel slits may be made therein for passing the belt under and out from under the 85 sides of the shirt-waist through said slits, where the skirt or pantaloons attach to the latter.

When the shirt-waist thus made is worn, the belt D, attached to the former at the back, 90 is passed beneath the straps or through parallel slits made in the shirt-waist, and interiorly buckled at the front ends to secure a girth hold or support on the hips of the wearer. The shirt-waist, being free upon the belt at the front 95 and sides, has a girth adjustment thereon, and

is also thereby connected with the belt, so as to transfer to it any tension made upon it by the weight of the attached skirt or pantaloons.

Having thus described our invention, what we claim, and desire to secure by Letters Patent, is—

In a shirt-waist, the combination of a belt exteriorly attached to the back of said shirt-waist, vertical straps on the exterior sides of said garment and passage-ways beneath them for the belt, vertical slit-openings made in said

garment at each side and near the bottom of the front opening for the passage inwardly of the belt, and buttoning attachments on the sides of said straps adapted to attach thereto 15 a skirt or pantaloons, as and for the purposes herein set forth.

WM. H. GALLUP.
LEE CHURCHILL.
